UNITED STATES PATENT OFFICE.

MATHIAS MATHIESON, OF ROCK ISLAND COUNTY, ILLINOIS.

IMPROVEMENT IN TRAM-STAFFS.

Specification forming part of Letters Patent No. 175,366, dated March 28, 1876; application filed August 4, 1875.

To all whom it may concern:

Be it known that I, MATHIAS MATHIESON, of Rock Island county, and State of Illinois, have invented a certain new and useful Improvement in the Miller's Staff or Level; and I do hereby declare that the following is a full and exact description thereof, which will enable others skilled in the art to which it pertains to make and use the same, reference being had to the accompanying drawings, and to the letters of reference marked thereon, which form a part of this specification.

Figure 1 is a perspective view of the staff or level A, showing the position of strip B, attached to the under surface when used for a level. Fig. 2 is a like view of same when used to obtain a concave or dishing of the stone.

Corresponding parts of the same are denoted by like letters of reference.

This improvement relates to a certain improvement in the staff or level A used by millers in dressing millstones; and it consists of a level, constructed with the strip B, attached by screws about seven inches from each end, leaving the space between the screws free, so that it can be used for the purpose hereinafter set forth. In the center of strip B, on its upper surface, is embedded a nut, d d, and also one corresponding in staff A with reverse

thread. Passing through staff A, and working in these nuts, is thumb-screw C, which, by turning, presses the strip B downward, making a perfect convex surface of any depth desired. By a reverse motion of screw, strip B is brought again to a level.

This device being of such construction, as already described, is designed principally for use in dressing millstones, and where it is desired to have a concaved or dished surface; and, when dressed in this manner, it is contended that better flour is made, the stones less liable to heat, and less dust arises from grinding.

This device being of such construction, as already described, when applied in the manner used for leveling, will give such concave or dish to the stone or any other substance as may be desired.

Having thus described my invention, what I claim, and desire to secure by Letters Patent, is—

The strip B, constructed substantially as and for the purpose and in the manner specified and set forth.

MATHIAS MATHIESON.
